DESK CONSTRUCTION

Bayard E. Richardson and Richard W. Willey,
Grand Rapids, Mich.

Application March 7, 1938, Serial No. 194,325

14 Claims.

(Cl. 45—6)

This invention relates to desks and is primarily concerned with the production of a very simply constructed, economically made, yet exceptionally strong desk structure and one which presents a very pleasing appearance.

An understanding of the invention and the structure embodying the same may be had from the following description, taken in connection with the accompanying drawings, in which:

10 Figs. 1 and 2 are perspective views from the front and from the back of the desk, respectively.

Fig. 3 is a perspective view illustrating the desk pedestals and the manner in which they are connected and assembled.

15 Fig. 4 is a longitudinal vertical section on a plane back of the front edge of the desk.

Fig. 5 is a transverse vertical section through the desk on a plane between the pedestals.

20 Fig. 6 is a perspective view illustrating the manner in which a pedestal separate from the connecting and bridging structure is assembled therewith, and

Fig. 7 is a perspective view of one form of cabinet which may be used in the desk structure at the rear of the desk well.

25 Like reference characters refer to like parts in the different figures of the drawings.

The desk comprises in its ordinary form, two spaced apart pedestals with a top thereover and with a bridging and connecting structure between the pedestals located preferably between the front and rear ends of said pedestals. Of course, the desk has the usual complement of drawers and slides in the pedestals and one between the pedestals above the well. Each pedestal includes a front post 1 and a rear post 2 at its outer side between which at a distance above their lower ends a horizontal bar 3 is permanently connected, while above said bar and between the posts is a side panel 4, at the inner side of which the usual drawer slides 5 are secured. A vertical back 6 closes the rear end of each pedestal, said back at its front side and adjacent its inner edge having a vertical bar 7 connected therewith, said bar being glued to the inner side of the inner side 8 of the pedestal.

30 In practice the side 8 is substantially one-fourth of an inch thick and of veneer and at its lower edge portions is curved toward the outer side 4 of the pedestal, as indicated at 9. A flat bar or board 10 is secured to the front side of the post 1 at one end and extends to and is permanently connected at its inner end portion with the lower front edges of the inner side 8 of the pedestal, 35 as fully shown in Figs. 3 and 6. Drawer guides 5 are likewise secured to the side 8 of the pedestal at the inner side thereof directly opposite the like guides 5 at the inner side of the panel 4.

The inner side member 8 of the pedestal at 40 its lower portion and a distance in front of its

rear edge has a rectangular opening 11 cut therethrough, from the rear end of which a vertical groove 12 extends to a rectangular mortise 13 cut in the upper edge of said side 8; while in direct horizontal alinement with the mortise 13 a similar mortise 14 is cut in the vertical portion of the uppermost drawer guide 5 at the inner side of each of the end panels 4 of each pedestal. The opening 11 is in front of the groove 12 and the mortises 13 and 14 back thereof (see Fig. 6). 10 The bridging and connecting truss member which extends between and is connected to the pedestals and is used to secure and assemble them together, in structure comprises an upper flat bar 15, a lower flat bar 16 of substantially identical structure as the bar 15, and a vertical panel 17 which may be of veneer and is relatively thin, in practice having a thickness dimension of approximately one quarter of an inch. The panel 17 has a length equal to the distance apart that the 20 inner sides of the pedestals are to be spaced. At its upper edge it is secured to the front edge of the upper bar 15 and at its lower edge to the rear edge of the lower bar 16. A covering strip 18 (Fig. 5) is secured at the lower edge of the panel 17 and at the rear side thereof.

25 In the assembly of the pedestals with the bridging member described, the projecting end portions of the bar 16 pass through the rectangular openings 11 in the sides 8 and the similar portions of the upper bar 15 pass through the mortises 13. The pedestals are moved toward the panel 17 until the vertical edges thereof are received in the grooves 12, whereupon the ends of the bars 15 enter the mortises 14 and lie above the uppermost drawer guides 5 at the inner sides 30 of the end panels 4, and the ends of the bars 16 lie above the bottom bars or rails 3 of the pedestals. Sand bars 15 and 16 may be very securely connected with said drawer guides and rails 35 by screws or other suitable fastenings. Likewise, the bars may be connected with the drawer guides 40 5 carried by the inner sides 8 of the pedestals. This assembles the pedestals with the bridging and connecting truss as shown in Fig. 3, with the panel 17 forming the rear side of the well between the pedestals, and with the bar 16 extending forwardly from the lower edges of the panel 17 between the pedestals. It is evident that the usual sliding drawers 19 may be put 45 in the pedestals at their open front sides and will go between the end portions of the bars 15 and 16. A drawer support and guide 20 may also be attached at the inner side of each of the sides 8 of the pedestals in front of the panel 17 50 (Fig. 5) for carrying the well drawer 21 (Fig. 1); and desk slides 22 at the upper end of each pedestal may be carried by the upper guides 5 underneat the top 23 and in front of the end 55 portions of the upper bar 15. A top 23 covers 60

the upper ends of the pedestals and the well portion of the desk in the usual manner and may be secured in accordance with conventional practice.

5 The desk as thus constructed has a space underneath the top back of the panel 17 wherein a cabinet may be placed if desired. In Fig. 7 one type of cabinet is shown having vertical ends 24, a bottom 25, a top 26 and a pigeon-hole compartment structure 27 within the space enclosed by the frame provided by said ends, top and bottom. The upper member 26 is narrower in width than the bottom 25 by a distance equal substantially to the width of the bar 15 which extends rearwardly from the panel 17, so that 10 when the cabinet is located underneath the rear portion of the top between the pedestals, the front edge of the upper member 26 comes against the rear edge of the bar 15, as in Fig. 5. The cabinet is preferably suspended from the top 23, as shown in Fig. 5, but of course is not necessarily subject to this one single means of support or connection. The cabinet as to its interior structure may take many forms, it may include drawers, have doors to close its rear side, or otherwise. The desk without such cabinet is a complete and finished article and the cabinet may be used or it may be not, as may be desired.

30 The desk structure described is of a particularly economical construction, the advantages of simplicity in structure and in assembly are evident. The bridging and connecting truss between the pedestals and located as it is between the front and rear ends of said pedestals provides a very strong structure and one which is capable of sustaining very long and effective use.

35 The invention is defined in the appended claims and is to be considered comprehensive of all forms of structure coming within their scope.

We claim:

40 1. In a desk structure, two spaced apart desk pedestals, and connecting supporting bars, one above the other, said bars being located in front of the rear ends of said pedestals and extending between the pedestals and secured at their ends to the outer sides thereof.

45 2. In a desk, two spaced apart desk pedestals, and upper and lower bars extending between the pedestals and through the inner sides of said pedestals and having connection to said pedestals at their ends and between their ends at the inner sides of the pedestals.

3. In a desk, spaced apart desk pedestals adapted to receive drawers, and connecting bars, one located at the upper portion of the pedestals and extending between the same and to the outer sides of each of said pedestals, and the other being located at the lower part of the pedestals and extending through the inner sides and substantially to the outer sides of said pedestals and permanently secured to said pedestals at their outer ends and at the inner sides of the pedestals.

46 4. A construction containing the elements in combination defined in claim 3, said bars being located between the front and rear ends of said pedestals.

5. In a desk structure, two spaced apart desk pedestals each adapted to receive drawers and to have a top applied thereto over said pedestals and over the space between them, a bar located immediately underneath the top and extending from the outer side of one pedestal to the outer

side of the other, the inner sides of the pedestals being recessed for reception of said bar, a second bar located below the first bar extending through the inner sides of the pedestals and at its ends extending to the outer sides of said pedestals and means securing said bars to the pedestals, said bars being located in front of the rear ends of said pedestals.

6. A construction containing the elements in combination defined in claim 5, the inner sides 10 of each of said pedestals being vertically grooved, and a panel having its vertical edges received in said grooves and extending between said upper and lower bars and secured thereto at its upper and lower edges, respectively.

7. In a desk, a pedestal, upper and lower bars extending from the outer side of said pedestal and through the inner side of the pedestal and beyond the same, said bars being located in front of the rear end of the pedestal, said pedestal being adapted to receive drawers slidably inserted therein at its front end, the rear portions of the drawers at their inner position being below the upper bar and above the lower bar, and a top covering the upper side of said pedestal and extending laterally over said bars, as specified.

8. In a desk, spaced apart desk pedestals having open ends into which drawers are adapted to be slidably received, vertically spaced bracing means extending between the inner sides of the 30 pedestals and through said inner sides substantially to the outer sides thereof and having connection to said inner and outer sides of the pedestals, and a top covering the upper ends of the pedestals and the space between.

9. A construction containing the elements in combination defined in claim 8, said bracing means being located a distance in front of the rear ends of said pedestals.

10. A construction containing the elements in combination defined in claim 8, said bracing means being located a distance forwardly of the rear ends of the pedestals and including a substantially vertical panel extending between the inner sides of said pedestals.

11. A desk comprising two spaced apart pedestals, a top covering said pedestals and the space between them, spaced bracing means extending between said pedestals, a vertical panel extending across the space between said pedestals and between said bracing means only and located inwardly from the back sides of said pedestals, and a cupboard structure located in the rear of said vertical panel between said pedestals and beneath said top.

12. The elements in combination defined in claim 11 in which said cupboard structure is secured to and suspended from the underside of said top.

13. The elements in combination defined in claim 11 in which said panel constitutes the inner closure of said cupboard structure.

14. A desk construction comprising, spaced apart pedestals, bracing means extending between the inner sides of the pedestals and through said inner sides substantially to the outer sides thereof, a top covering the upper ends of said pedestals and the space between, and a partition extending between the pedestals spaced forwardly from the rear ends thereof to provide 70 shelf space.
